UNITED STATES PATENT OFFICE.

CHARLES R. GETHER, OF MILWAUKEE, WISCONSIN.

ROTARY PUMP OR AIR-COMPRESSOR.

971,188.

Specification of Letters Patent. Patented Sept. 27, 1910.

Application filed June 6, 1910. Serial No. 565,182.

To all whom it may concern:

Be it known that I, CHARLES R. GETHER, a citizen of the United States, residing at Milwaukee, county of Milwaukee, and State of Wisconsin, have invented new and useful Improvements in Rotary Pumps or Air-Compressors, of which the following is a specification.

My invention relates to improvements in rotary pumps or air compressors, in which two revoluble pistons are so connected together that they are caused to move alternately faster and slower around a common center within an inclosing cylinder, whereby the fluid to be acted upon will be caused to enter the widening space between the opposing sides of said pistons as they separate, while the fluid which has previously entered between the opposite sides of said pistons will be simultaneously discharged and my present improvement pertains more especially, among other things, to the peculiar construction and relative arrangement of the pistons, inlet and outlet ports and by passes to each other and the piston inclosing cylinder, whereby the fluid to be acted upon will at all times have free access both to and from the cylinder regardless of the relative position of the pistons to each other and to the main outlet ports, and whereby an ample surface area is provided between such ports to prevent the liability of the air or liquid from being forced past the pistons from one of said ports to the other or from the outlet port to the space between the pistons as they begin to separate.

It will be understood that although the inlet port may be sufficiently open for the admission of fluid when the two pistons first separate, soon after such pistons separate said port becomes partially closed by the slower moving piston in front of the same, whereby the free admission of fluid is obstructed before the fast moving piston has completed its revolution, whereby with this class of devices as heretofore constructed, the supply of fluid is cut off or limited whereby a partial vacuum is produced. Also, that as the main outlet port is not sufficiently wide open to allow the liquid or air to be discharged freely at the beginning of the accelerated movement of the rapidly moving piston, especially when pumping liquids, a concussion or water hammer is produced as such rapidly moving piston approaches the slowly moving piston, which

concussion is liable to wreck or damage the machine. Also, that when compressing air or other elastic fluids, by reason of the narrow space between the outlet port and the point of separation of the pistons the leakage from the outlet port has a tendency to refill the space between said pistons, expand, and either escape through the inlet port or remain where it is and be again and repeatedly compressed.

One of the primary objects therefore of my present improvement is to provide branch ports or by passes, which are so located that when the primary ports are partially or wholly closed by the moving pistons, the fluid will be free to temporarily enter and escape through such branch ports, whereby the pump or air compressor will operate smoothly, easily and with the highest efficiency, and the danger from concussion or water hammer heretofore experienced in machines of this class is entirely overcome.

My invention is explained by reference to the accompanying drawings, in which—

Figure 1 is a side view, part in section. Fig. 2 is an end view. Fig. 3 is a transverse section, drawn on line $z-z$ of Fig. 1. Fig. 4 is a longitudinal section of the pistons. Fig. 5 is a perspective view of one of the pistons. Fig. 6 is a side view of one end of the cylinder with a portion of the covers of the ports and by-passes removed, the position of the pistons being indicated by dotted lines. Figs. 7 to 14 are diagrammatic views of the cylinder, pistons, ports and by-passes, showing the relative position of the pistons to each other and said ports and by-passes during one complete revolution of one of said pistons.

Like parts are identified by the same reference numerals throughout the several views.

1 is a driving shaft which is adapted to be driven by a pulley 2, or in any other convenient manner.

A and B are pistons of similar construction. The piston A is rigidly connected to the shaft 5, and the piston B is connected in like manner to the shaft 6, and said pistons are centrally supported in alinement with each other by the trunnion 7. Motion is communicated from the shaft 1 to the piston member A through the differential gears 8 and 9 and shaft 5, while a similar movement is simultaneously communicated to the pis-

ton member B from the shaft 1 through the differential gears 10 and 11 and shaft 6.

The relative arrangement of the two sets of differential gears 8 and 9 and 10 and 11 to each other is such, that while the shaft 1 moves at a uniform speed, the respective shafts 5 and 6 and piston members A and B move alternately faster and slower, one of said piston members moving slowly and 10 making a small part of a revolution only, while the other performs a complete revolution, whereby the fluid between the front side of the rapidly moving piston member and the rear side of the slowly moving piston member is forced out as the rapidly moving piston approaches the other, while 15 a partial vacuum is simultaneously formed between the rear side of the rapidly moving piston and the front side of the slowly moving piston, whereby air or water is caused to flow into the space between such pistons preparatory to being forced out as soon as the relative speed of said piston members is reversed. Thus the fluid acted 20 upon is continuously being drawn into the space upon one side of said pistons, while it is simultaneously forced from the space upon the opposing sides of said pistons. The pistons and their supporting shafts are 25 inclosed by the cylinder 15, and the respective ends of the cylinder are closed by the end members 16, 16, which members serve as cylinder heads, as supports for the respective ends of the shaft 1 and as bearings 30 for the ends of the shafts 5 and 6.

29 is a support for one end of shafts 1 and 5 and together with the trunnion 7 serves to keep said shafts 5 and 6 in alignment with each other.

40 20 is an inlet port through which fluid is led to the cylinder preparatory to being acted upon by the pistons.

21 is an outlet port through which the fluid is forced from the cylinder.

45 While the respective inlet and outlet ports may be formed in the cylinder heads, they are preferably formed in the cylinder 15 and are adapted to be alternately opened and closed by the revolving pistons as they 50 pass in front of them.

In view of the fact that the inlet port 20 is partially closed by the slowly moving piston A before it is overtaken by the fast moving piston B, (see Fig. 3), it becomes necessary in order to admit a full supply of fluid into the space C to provide an auxiliary inlet port or by pass 22, whereby fluid is free to enter the space C after the piston A has entirely closed said port 20. The by 55 pass 22 is provided with an inward opening check valve 23, which is closed by the fluid pressure within the space C or by other means and prevents the escape of fluid from such space before the piston A has 60 passed the inlet end of said by pass. In

view also of the fact that the outlet port 21 is nearly closed by the piston A at the beginning of the accelerated movement of the piston B, I have provided an auxiliary port or by pass 24, whereby the fluid in the space 70 D is free to escape through said by pass into the port 21 until said port 21 is more widely opened by the passage of the slowly moving piston A. 25 is an outward opening check valve which serves to prevent fluid which 75 has been driven out through the port 21 by the piston B from returning to the cylinder through the by pass 24. In view of the fact that the piston A will have passed the port 21 and that said port will be closed 80 by the piston B before said pistons come together, a small quantity of fluid would, unless otherwise provided for, remain trapped between said pistons after said port 21 is closed. It therefore follows that unless such 85 trapped fluid is released, it will, when a liquid, cause a concussion or so called water hammer, which is liable to break the pump and injuriously affect its working. Also that in case air is being compressed, such 90 trapped air will be repeatedly acted upon and permitted to expand without escaping from the cylinder. In view of these facts, I have provided an auxiliary port 26, which is connected with the port 21 by the by pass 95 27, (see Fig. 6), and said port 26 is so located in advance of and overlapping the port 21 that such fluid as would otherwise become trapped in the space between said pistons A and B will be free to pass out 100 through said port and by-pass to the port 21, whereby the concussion and noise is prevented and the machine is caused to move smoothly and with the highest efficiency. This port is provided with an outward opening check valve 28 which prevents the fluid from reentering the space between the pistons from which it has been expelled.

105 Referring briefly to the diagrammatic views shown in Figs. 7 to 14, Fig. 7 shows 110 the relative position of the pistons A and B to the ports and by-passes at the beginning of the accelerated movement of the piston B, the inlet port 20 and the outlet port 21 being closed by the pistons A and B, while the 115 fluid in front of B passes out through the by-pass 24 and a partial vacuum is formed in the space C between the pistons A and B. Figs. 8 and 9 show the relative position of the pistons as the inlet port 20 is opened, 120 while the fluid is being forced out both through the port 21 and by-pass 24 and admitted through the port 20. Fig. 10 shows the relative position of the pistons after both inlet and outlet ports are partially open and 125 both by passes 22 and 24 are also opened. Figs. 11 and 12 show the relative position of the pistons to each other and the ports after the piston B has closed the by pass 24. Fig. 13 shows the relative position of the pistons 130

to each other after the outlet port 21 is closed entirely at which point the fluid which becomes trapped between said pistons, passes out through the port 26, and thence back to the port 21 through the bypass 27 until both pistons come close together as shown in Fig. 14, while Fig. 14 shows the position of the piston A when and after it has been overtaken by the piston B, and until the pistons again begin to separate at which point the relative position of said pistons is completely reversed. As soon as the piston B has thus completed its revolution and overtaken the piston A, the speed of the piston A will in like manner be accelerated until it overtakes the piston B and the movement thus described will be continuously repeated.

It will be understood that by thus using the several auxiliary ports and bypasses, I am enabled to make the main ports 20 and 21 comparatively narrow without restricting or interfering with the free passage of fluid to and from the cylinder and that by thus making such ports comparatively narrow, a larger surface area is provided between said ports than it would be possible to provide with larger ports, whereby there is less danger than there might otherwise be of the fluid, which is under pressure, from escaping from one port to the other past said pistons or from the outlet port to the opening space between the pistons. For example, if the port 21 were to be increased in width to correspond with the width of the auxiliary port 26 and port 21 combined (as might otherwise be required to prevent the trapping of fluid between said pistons as they come together), there would not remain enough surface area between the inlet and outlet ports to prevent the escape of fluid from one port to the other or from the outlet port to the opening space between the pistons, while by forming the auxiliary ports and bypasses and providing the same with check valves as shown, I am enabled as stated to locate said main ports at a sufficient distance apart to prevent such escape of fluid and the loss of power incident thereto.

While my device is adapted to be used both as an air compressor and as a liquid pump for brevity of description it is herein-after referred to in the claims as a pump.

Having thus described my invention, what I claim as new, and desire to secure by Letters Patent, is—

1. In a pump, the combination with a cylinder, of two pistons extending from its axis to its circumference and from end to end and having substantially equal circumferential width mounted therein, and adapted to rotate about said axis, means for continuously rotating the pistons in the same direction at alternately faster and slower

speeds so that each shall move faster while the other moves slower, with such amplitudes of the movements of each kind that adjacent faces of the pistons will alternately approach each other until they are close together and recede from each other until the opposite faces are close together; the cylinder having inlet and outlet ports which are controlled by the pistons and lie close to and on opposite sides of the space within which the piston faces come close together and within the space bounded by the more remote faces of the pistons, when the pistons are nearest to each other, whereby the inlet port is opened between the receding faces of the pistons at practically the beginning of the receding movement and constantly closed to the approaching faces and the outlet port is opened between the approaching faces of the pistons until the end of the approaching movement and is constantly closed to the receding faces, the ports being separated by a considerable space on the interior surface of the cylinder which is covered by the pistons when they come close together.

2. In a pump, the combination with a cylinder, of two pistons extending from its axis to its circumference and from end to end and having substantially equal circumferential width mounted therein, and adapted to rotate about said axis, means for continuously rotating the pistons in the same direction at alternately faster and slower speeds so that each shall move faster while the other moves slower, with such amplitudes of the movements of each kind that adjacent faces of the pistons will alternately approach each other until they are close together and recede from each other until the opposite faces are close together, inlet and outlet ports communicating with said cylinder adapted to be alternately opened and closed by said pistons as the latter revolve in front of them, an additional outlet port located at a point slightly in advance of and overlapping said main outlet port at and before the junctural point of said pistons, a check valve located in said port and a bypass leading from said advanced port back to said main outlet port adapted to permit the fluid which would otherwise be trapped between said pistons to escape after said main outlet port is closed by the fast moving piston.

3. In a pump, the combination with a cylinder, of two pistons extending from its axis to its circumference and from end to end and having substantially equal circumferential width mounted therein, and adapted to rotate about said axis, means for continuously rotating the pistons in the same direction at alternately faster and slower speeds so that each shall move faster while the other moves slower, with such amplitudes of the movements of each kind that adjacent faces

- of the pistons will alternately approach each other until they are close together and recede from each other until the opposite faces are close together, an auxiliary inlet port 5 adapted to admit fluid between said pistons after the main inlet port is partially closed by the slowly moving piston and a check valve located in said auxiliary inlet port.
4. In a pump, the combination with a cylinder, of two pistons extending from its axis to its circumference and from end to end and having substantially equal circumferential width mounted therein, and adapted to rotate about said axis, means for continuously rotating the pistons in the same direction at alternately faster and slower speeds so that each shall move faster while the other moves slower, with such amplitudes of the movements of each kind that adjacent faces of the pistons will alternately approach each other until they are close together and recede from each other until the opposite faces are close together, an outlet port and by pass adapted to permit of the escape of fluid from between said pistons before the main outlet port has been fully opened by the passage of the slowly moving piston and a check valve adapted to close said outlet port.
5. In a pump, the combination with a cylinder, of two pistons extending from its axis to its circumference and from end to end and having substantially equal circumferential width mounted therein, and adapted to rotate about said axis, means for continuously rotating the pistons in the same direction at alternately faster and slower speeds so that each shall move faster while the other moves slower, with such amplitudes of the movements of each kind that adjacent faces of the pistons will alternately approach each other until they are close together and recede from each other until the opposite faces are close together, inlet and outlet ports communicating with said cylinder adapted to be alternately opened

and closed by said pistons as the latter revolve in front of them, an auxiliary inlet port, a check valve located in said inlet port adapted to admit fluid between said pistons after the main inlet port is practically closed by the slowly moving piston, an outlet port and by pass, a check valve located in said outlet port adapted to permit of the escape of fluid before the main outlet port is fully opened, and an additional outlet port located at a point slightly in advance of and overlapping said main outlet port at and just before the junctual point of said pistons a check valve located in said additional port and a by pass leading from said additional port back to said main outlet port and adapted to permit the fluid which is trapped between said pistons to escape after said main outlet port is closed by the fast moving piston.

6. In a pump of the described class, the combination of a cylinder provided with inlet and outlet ports communicating with its interior, a driving shaft, two revoluble pistons, a trunnion connected with the opposing ends of said pistons, two piston supporting shafts respectively connected with said pistons, end members connected with and adapted to close the respective ends of said cylinder, and a shaft supporting standard, one of said end members and said standard being adapted to support one end of said driving shaft and one of said piston supporting shafts, the other end member being adapted to support the other end of said driving shaft and together with the trunnion to support the other piston supporting shaft whereby said pistons and piston supporting shafts are supported and retained in alignment with each other.

In testimony whereof I affix my signature in the presence of two witnesses.

CHARLES R. GETHER.
